REFRIGERATION-CHILLING APPARATUS

Humphrey L. Nash, Shaker Heights, Ohio

Application September 3, 1932, Serial No. 631,724

8 Claims. (Cl. 62—169.1)

This invention relates to refrigeration-chilling apparatus, and more particularly apparatus for chilling articles or materials by exposure to suitable media; and it is among the objects of the invention to provide a construction presenting thorough exposure to refrigeration, while holding uniformly the articles undergoing treatment. A further object is the provision of apparatus allowing an advantageous latitude of capacity range. Other objects and advantages will appear as the description proceeds.

To the accomplishment of the foregoing and related ends, the invention, then, comprises the features hereinafter fully described, and particularly pointed out in the claims, the following description and the annexed drawing setting forth in detail an illustrative embodiment of the invention, this being indicative however, of but one of the various ways in which the principle of the invention may be employed.

In said annexed drawing:

Fig. 1 is a side elevational view of an embodiment of the invention; and Figs. 2 and 3 are perspective detail views.

Referring more particularly to the drawing, there is shown a plurality of frames 2, each face or top and bottom of which is closed by a chill leaf 3, and passage-ways 4 for cooling media are provided by the leaves. Guide surfaces of suitable form align the leaves to the frames for adequate closure of these as units, and in the form illustrated such guides may be placed at the corners and on the frames as projecting members 5, of dimensions to receive the respective chill leaf corners, allowing the leaves to seat down to the frames and against the articles or material therein. Conveniently, the passage-ways 4 may be determined by spacers 6 which may be placed on one or both of adjacent leaf members, preferably on both. Correspondingly, when each frame is assembled with the closure chill leaves, and such units are stacked with adjacent units, as indicated in Fig. 1, passage-ways or channels 4 are provided such that each unit of the stack is in free exposure on all sides. For binding the assemblage together, suitable binder means is provided, and in the particular form illustrated, this comprises standards 7 at each side of the stack of frames, and having bottom and top yokes 8 and 9 respectively. Take-up nuts 10, preferably with manipulating-handles 11, and screw-threadedly engaging the standards 7, complete the binder means.

The manner of use of the device will be readily

understood from the foregoing. The articles or material to be treated are placed successively in a frame 2 assembled with its bottom leaf 3, and a corresponding leaf is then applied to the top thereof, and successive frame-units are thus filled and stacked. For example, if it is desired to chill bacon to prepare the same for a slicing machine, the pieces of bacon are positioned in respective frames 2 assembled with the bottom leaf 3, the top leaf is applied, successively charged units brought together in this manner are stacked within the standards 7, the top yokes 9 are applied thereto, and the nuts 10, and the latter are turned down to a desired degree. The entire stack may then be conveniently handled into the chilling compartment, and by reason of the thorough exposure of the chilling media through the passage-ways 4 and on all sides of each unit with its contained material, the temperature of the latter is readily brought uniformly to the desired point, and irrespective of the number of pieces being treated in any given stack, or the total number in the compartment, all are treated uniformly. To the extent that molding pressure is desired, the take-up means as exemplified in the compression nuts 10 may be availed of, and in such manner a uniformity of appearance of the treated bacon slabs may be had. Again, whether the capacity requirements be larger or smaller, the appropriate number of frame units can be assembled and so employed.

Other modes of applying the principle of the invention may be employed, change being made as regards the details described, provided the means stated in any of the following claims, or the equivalent of such be employed.

I therefore particularly point out and distinctly claim as my invention:—

1. Refrigeration-chilling apparatus, comprising a frame limiting the lateral dimensions of material placed therein and having opposite open faces, a chill leaf for closing each face thereof, and regulating take-up means for binding the assemblage together.

2. Refrigeration-chilling apparatus, comprising a plurality of frames limiting the lateral dimensions of material placed therein and having opposite open faces, a pair of chill leaves for closing the open faces of each frame, passage-ways for cooling media between the leaves stacked adjacent each other in assembly, and means for binding the assemblage together.

3. Refrigeration-chilling apparatus, comprising a plurality of frames limiting the lateral

dimensions of material placed therein and having opposite open faces, chill leaves co-acting with the frames to close the open faces thereof, spacers between adjacent leaves forming passage-ways for cooling media, and means for binding the assemblage together.

4. Refrigeration-chilling apparatus, comprising a plurality of frames limiting the lateral dimensions of material placed therein and having opposite open faces, chill leaves co-acting with the frames to close the open faces thereof, spacers attached to each leaf forming passage-ways for cooling media, and means for binding the assemblage together.

5. Refrigeration-chilling apparatus, comprising a plurality of frames limiting the lateral dimensions of material placed therein and having opposite open faces, guides on each frame, a pair of chill leaves slideable in the guides of each frame to close the open faces thereof, spacers between adjacent chill leaves, and means for binding the assemblage together.

6. Refrigeration-chilling apparatus, comprising a plurality of frames limiting the lateral

dimensions of material placed therein and having opposite open faces, corner guides on each frame, a pair of chill leaves slideable in the guides of each frame to close the open faces thereof, spacers between adjacent chill leaves, and means for binding the assemblage together.

80

7. Refrigeration-chilling apparatus, comprising a stack of frames limiting the lateral dimensions of material placed therein and having opposite open faces, chill leaves co-acting with said frames to close the open faces thereof, standards at each side of said stack of frames, bottom and top yokes therefor, and take-up nuts on said standards.

85

8. Refrigeration-chilling apparatus, comprising a stack of frames limiting the lateral dimensions of material placed therein and having opposite open faces, corner guides on each frame, a pair of chill leaves co-acting in said guides to close the open faces thereof, spacers attached to each chill leaf, standards at each side of said stack of frames, bottom and top yokes therefor, and take-up nuts on said standards.
